ABSTRACT

A golf club swing guide includes track members for guiding the golf club through a grooved swing. The track members includes first and second arcuate track members mounted on a support adjustable in inclination to conform to the swing planes of the golf swing and a given length of golf club. One of the arcuate track members defines the backswing of the golf club and the second track member defines the power swing of the golf club. The arcuate track members join one another adjacent their upper and lower ends respectively and spring-biased switches are provided to insure the direction of the golf club and more particularly the guide thereon engaging the track members into the proper backswing and power swing tracks.

GOLF CLUB SWING GUIDE

BACKGROUND OF THE INVENTION

1. Field of the Invention

This invention relates to a golf swing guide means of the type employed to assist a player in the proper execution of a golf stroke.

2. Description of the Prior Art

Prior structures of this type have employed a curving track guide means arranged to cooperate with a golf club or a simulated club so as to direct the same in a desirable path both with respect to the backswing and the power swing. (See U.S. Pat. Nos. 1,634,102, 2,813,721, 2,868,543, 3,341,208 and 3,489,416.) This invention introduces the novel feature of providing guiding tracks and means in connection therewith for directing the golf club or simulated golf club into the proper trackways defining a proper backswing and a proper forward or power swing.

SUMMARY OF THE INVENTION

A portable inclined frame carries a trackway substantially circular in overall appearance and having portions thereof separated into two trackways, one of which defines the proper path for a proper backswing of a golf club and the other of which defines a proper path for the forward or power swing of the golf club. The two sections are separated from the other section of the generally circular trackway by switch means arranged to direct the golf club into the proper trackway depending upon the direction of motion of the golf club along the trackway.

Description of the Drawings

FIG. 1 is a prospective elevation of the golf club swing guide.

FIG. 2 is an enlarged detail on line 2—2 of FIG. 1.

FIG. 3 is an enlarged detail on line 3—3 of FIG. 1.

FIG. 4 is an enlarged detail on line 4—4 of FIG. 1.

FIG. 5 is an enlarged detail of a switch as seen on line 5—5 of FIG. 1.

FIG. 6 is an enlarged detail of a secondary switch as seen at line 6—6 of FIG. 1.

FIG. 7 is an enlarged detail of a modified trackway and guide corresponding generally with FIG. 2 of the drawings.

FIG. 8 is a detail of the modified trackway of FIG. 7 and taken on line 8—8 thereof.

FIG. 9 is a detail of a modified switch comparable with FIG. 5 of the drawings.

FIG. 10 is a detail of a modified secondary switch comparable with FIG. 6 of the drawings.

DESCRIPTION OF THE PREFERRED EMBODIMENT

In its simplest form the golf club swing guide disclosed herein comprises an inclined frame 10 positioned on a U-shaped base 11, the upper ends of the inclined frame 10 being supported on vertical posts 12 and a transverse interconnecting frame member 13. The inclined frame members 10 and the vertical posts 12 may be and preferably are adjustable so that the inclination of the inclined frame 10 may be adjusted.

The inclined frame members 10 and the transverse interconnecting frame member 13 directly support a plurality of trackway sections 14 which are positioned in end to end arrangement to form a continuous trackway in which a golf club guide member 15 is movably engaged. Enlarged details of the trackway sections 14 may be seen in FIGS. 2, 3 and 4 of the drawings and by referring thereto it will be seen that the trackway sections 14 are preferably formed of slotted tubing, the slot therein being longitudinal and defined by inturned flanges 16. The golf club swing guide member 15 has a transverse axle 17 on the end thereof disposed within the trackway sections 14 with a pair of rollers 18 secured thereto. The other end of the golf club guide member 15 has a circular clamp 19 which is adapted to be secured to the shaft of a golf club 21.

By referring again to FIG. 1 of the drawings it will be seen that the trackway sections 14 attached to the right half of the inclined frame 10 and the transverse interconnecting frame member 13 define somewhat more than half a circle and are shaped to match the follow-through swing of the golf club 21 after it has struck a golf ball positioned immediately in front of the guide. The actual configuration of the trackways 14 is preferably that of a proper swing by an individual who will use the golf club swing guide for perfecting the proper swing path. The left hand portion of the trackway sections 14 is formed of two sections, 14a and 14b which are joined to one another at their upper and lower ends and spaced with respect to one another therebetween and both of which sections 14a and 14b are arcuate. The section 14a defines a trackway for the backswing, while the section 14b forms a trackway for the forward or power swing of the golf club 21. Switch means 22 and 23 positioned at the junctions of the trackways 14a and 14b at their upper and lower ends respectively insure the guidance of the golf club into the proper trackway for guiding the golf club in the proper swing stroke.

By referring to FIG. 5 of the drawings, an enlarged detail of the switch means 22 may be seen and it will be observed that the upper end of the trackway 14a extends through the area of a switch plate 22a and into an extension trackway 14c, while the upper end of the trackway 14b partially connects with the trackway section 14c and is connected therewith by the proper placement of the switch plate 22a. Solid line representation in a portion of the trackway 14a at the junction of the section 14c indicates the normal position of the switch plate 22a as it is urged to such position by a spring 24 positioned about a pivot 25 in the switch means 22. Broken line illustrations of the switch plate 22a show it in depressed or lower position as occurs when the golf club guide moves upwardly as indicated by the arrow in the trackway 14a and moves the switch plate 22a to one side. When the golf club guide moves into the trackway section 14c the switch plate 22a returns to the position shown in solid lines so that when the forward or power swing stroke starts, it will guide the club into the trackway section 14b.

By referring now to FIG. 6 of the drawings the switch means 23 will be seen to connect the lower end of the trackway section 14a with the lower end of the trackway section 14b and the continuing half circular

trackway 14. The switch means 23 includes a pivot 26 mounting a switch section 26a which conforms with the trackway 14, 14a and 14b and which is arranged to be positioned as shown in solid lines in FIG. 6 so that it is normally positioned between the trackway section 14b and the trackway section 14 and thus provides an unbroken guide path for the golf club moving downwardly as shown by the arrow in the section 14b as occurs on the forward or power swing stroke, which stroke must continue uninterrupted into the section 14 on the right half of the golf club swing guide which defines the follow-through stroke and pattern.

Those skilled in the art will observe that the actual circular or curving pattern of the several trackway sections 14 can be shaped to match the proper swing pattern of an individual by photographing the individual in stop motion photography to provide a pictorial indication of the correct golf swing path which can then be used in shaping the trackway sections 14.

Those skilled in the art will observe that modifications in the structure hereinbefore described may be made without departing from the spirit of the invention and by referring to FIGS. 7-10 of the drawings one such modification may be seen. In FIG. 7 a supporting frame 28 is illustrated as formed of tubing with a continuously extending rod-like guide member 29 spaced therefrom and defining the golf club swing guide by means of a plurality of support arms 30. A C-shaped guide 31 slidably engages the rod 29 and is secured by way of a secondary arm 32 to a tubular clamp 33 which is secured to a golf club shaft 34. The guide rod 29 would be shaped in the same manner as the trackway 14 heretofore referred to and illustrated in FIG. 1 of the drawings.

By referring now to FIG. 8 of the drawings a planned view of a portion of the guide rod 29 may be seen spaced with relation to the supporting frame 28 and it will be observed that movement of the golf club shaft 34 will be guided therealong.

By referring now to FIG. 9 of the drawings a switch mechanism comparable with the switch means 22 as seen in FIGS. 1 and 5 of the drawings, and hereinbefore described, may be seen and it will be observed that a section 29a, of the guide rod 29, extends through the switch area while a switch section 29c is pivoted in the switch by a pivot 35. The arrangement is such that the golf club shaft 34 with its slide piece 31 engaging the rod 29 will move upwardly to the right on the section 29a of the guide rod and onto the section 29 deflecting the hinged section 29c which will then be moved back to the position shown in solid lines by a spring 36 around the pivot 35 so that on the beginning of the motion of the golf club to the left and downwardly in the forward or power swing stroke the guide 31 will follow the section 29c which is in end to end abutment with the intermediate continuing section of the guide rod 29b which leads downwardly to the second or lower switch mechanism as seen in FIG. 10 of the drawings.

By referring thereto it will be seen that a switch section 29d is pivoted on a pivot 37 and normally positioned as shown by the broken lines in FIG. 10 by a light spring 38 around the pivot 37 and so arranged that

it will be engaged and moved by the slide piece 31 into the position shown in solid lines in FIG. 10 when the golf club slide piece 31 slides downwardly therealong and onto the guide rod section 29 comprising the portion of the golf club swing guide in this modification that guides the follow-through stroke. The spring 38 will then position the switch section 29d to clear the path for the next swing. Grooves in the adjacent sections of the guide rod permit the sliding engagement of the slide piece 31.

It will thus be seen that a golf club swing guide has been disclosed which is preferably shaped to match the perfect swing pattern of a golfer and that by practicing with such a device, the golfer may perfect his swing pattern so that he will be able to utilize the same considerably more often in an actual golf game than has heretofore been possible. It will further be seen that the golf club swing guide, as disclosed herein, may be simply and economically formed from relatively few component parts.

Although but two embodiments of the present invention have been illustrated and described, it will be apparent to those skilled in the art that various changes and modifications may be made therein without departing from the spirit of the invention, and having thus described my invention what I claim is:

1. A golf swing practice device comprising an inclined support conforming generally to the plane of the golf swing, backswing track means and power swing track means, and extensions thereof for guiding a golf club through at least the backswing and power swing portions respectively of a golf swing, means mounting said track means on said inclined support, upper and lower portions of said backswing and said power swing track means communicating adjacent the intersections of the backswing and power swing track means and switch means at said intersections arranged to selectively interconnect said backswing and said power swing track means with said extensions thereof.

2. The golf swing practice device set forth in claim 1 wherein said backswing and said power swing track means each have club guiding means formed therein for guiding engagement with a golf club.

3. The golf swing practice device set forth in claim 2 and including a golf club, a guide of T-shaped configuration provided on said club, and said club guiding means including a slot in each of said track means and of generally inverted T-shaped configuration to accommodate said guide.

4. The golf swing practice device set forth in claim 3 and wherein said guide of T-shaped configuration includes rollers.

5. The golf swing practice device set forth in claim 2 including a golf club, a guide of a split tubular configuration provided on said club, and said club guiding means consisting of a rod, said split tubular guide being slidably engaged on said rod.

6. The golf swing practice device set forth in claim 1 and including a golf club, each of said track means being a flat arcuate slotted track member and said golf club having a track guide member shaped for engaging said slot in said track members.
